UNITED STATES PATENT OFFICE.

CHARLES E. GAFFNEY AND JOHN R. PETTIFORD, OF ST. LOUIS, MISSOURI; SAID PETTIFORD ASSIGNOR TO SAID GAFFNEY.

HOT-WATER AND VACUUM CLEANING SYSTEM.

1,053,375.

Specification of Letters Patent. Patented Feb. 18, 1913.

Application filed June 28, 1911. Serial No. 635,520.

To all whom it may concern:

Be it known that we, CHARLES E. GAFFNEY and JOHN R. PETTIFORD, citizens of the United States, residing in the city of St. Louis and State of Missouri, have invented a new and useful Hot-Water and Vacuum Cleaning System, of which the following is a specification.

This invention relates to hot water and vacuum cleaning systems, and its prime object is to provide a vacuum cleaning apparatus combined directly with a hot water heater, whereby a single generator or heater may be used for supplying hot water, and for creating steam pressure for a vacuum creating element in the vacuum cleaning apparatus.

There are other objects to be attained by the present invention, which will be apparent from the following detailed description, reference being made to the accompanying drawings in which—

Figure 1 is a side view, partially in section, showing the complete system; and Fig. 2 is a sectional view through the line 2—2 of Fig. 1, showing the back-pressure valve, and the connections therefrom to the valve in the fuel supply pipe.

The water tank 1 is supplied with water through the pipe 2, which is connected to a water supply main pipe 3. The water in the tank 1 is supplied to the generator or heater 4 through the pipes 5 and 6. It will be apparent that since the water supply tank 1 is elevated above the highest water level in the generator or heater 4 the hydrostatic pressure will be sufficient to maintain water, under pressure, in said generator or heater 4, at all times. The passage of water from the pipe 3 to the pipe 6 is controlled by a valve 7, which valve is held normally closed by an expansion spring 8, encircling a pin 9, which pin projects through the valve case 10.

A fuel supply pipe 11 supplies fuel of a liquid or gaseous character to a burner 12, supported adjacent to the lower part of the generator or heater 4. The said burner 12 is provided with a plurality of jets 13, which are suitably disposed in such a manner as to distribute the heat from the burner equally throughout the generator or heater 4. A pilot light 14 may be provided for igniting the jets 13 of the burner 12, when fuel is admitted thereto.

The generator or heater 4 and the burner 12 are inclosed in a housing or hood 15, which we prefer to make of two separated walls, with an air space between, as shown in Fig. 1, thus preventing radiation as far as possible. The housing or hood 15 is supported in any convenient manner, and we have here shown it mounted on a stand 16 of usual construction. It is obvious that the housing or hood 15 may be disposed with, but in practice it has been found to be advantageous for confining and equalizing the heat supplied to the generator or heater 4. The housing or hood 15 has a flue 17 leading from the top thereof, which is effective as a means for egress for the gas and fumes from the burner 12. This flue 17 may be provided with a damper 18 of usual type, by which the draft may be regulated.

We have illustrated a generator or heater 4 of preferred construction for use in the present system. The generator or heater 4 comprises a plurality of circular hollow chambers 19 supported in oblique adjustment, as clearly shown in Fig. 1 of the drawing. Each of the units 19 has several passages 20 therethrough, permitting the heat from the burner 12 to rise and be distributed uniformly throughout the generator or heater 4. The units 19 are connected by intercommunicating passages 21, so that the circulation of water or steam will be continuous, and free. A valve-controlled pipe 23 attached to the lower portion of the generator or heater 4, is for use in cleaning or draining the system. A pipe 24, terminating in a valve or faucet 25 is provided for drawing off hot water from the generator or heater 4. It will be understood that any other type or design of generator may be used, and that a full system of piping may be used instead of the single pipe 24, whereby water may be supplied throughout a building.

The fuel supply pipe 11 is controlled by a valve 26, which is actuated toward closed adjustment by means of a spring 27, encircling a pin 28. The pin 28 terminates adjacent to the pin 9, and co-operates therewith to open the valve 26, when the valve 7 is opened by the pressure of the water in the pipe 3. Said valve 26 may be independently operated by means of a draw chain 29, which passes over a sheave 30. It is apparent that the draw chain 29 may terminate,

and be operated from any desired location in the building in which the system may be installed. Between said valve 26 and the fuel burner 12, we provide an auxiliary valve 31, which is regulated through lever and link connections by pressure in the pipe 6. It is obvious that when the pressure in the generator or heater 4 is increased to such a point as will overcome the tension of the spring 32, the piston 33 will be raised, thereby regulating through the lever and link connection the amount of fuel that may pass through the valve 31. The tension of the spring 32 may be adjusted, so that the generator or heater 4 may carry any predetermined back-pressure, above which the valve 31 will operate. In this way a uniform steam pressure in the generator or heater 4 may be maintained, and substantially uniform temperature may be preserved therein.

The upper end of the generator or heater 4 opens into a globe chamber 34, which communicates by means of the passage 35 with the valve chamber 36. A by-pass connection 37 is provided between said passage 35 and the water supply tank 1. The valve chamber 36 is provided with a removable top 36^a, having a tubular extension 38, in which there is a tapering passage 39. A float device 40 within the valve chamber 36 has a pointed projection 41 extending into the passage 39 and constitutes a valve, which is normally closed and is effective to prevent any flow of water through said passage 39, since the water within the valve chamber upholds the float, and presses the projection 41 into the passage 39, thereby closing said passage. When steam is generated and rises into the valve chamber 36, the level of the water in said chamber lowers, and the float 40 automatically lowers with the water thereby opening the passage 23 into a pipe connection 42. The steam passes through an ejector or aspirator 43 in the pipe connection 42 into an outlet pipe 44 creating a suction or draft through a suction pipe or main 45 to which any suitable sweeper or suction head may be connected. The pipe 44 constitutes a discharge pipe into and through which the particles brought in through the pipe 45 will be discharged by the pressure or draft from the ejector or aspirator 43.

From the foregoing it will be understood that the tank 1 is filled from the main water supply 3, and that the generator or heater 4 is supplied with water at uniform pressure through the pipe connection 5-6, and that the valves 7, 25, 26, and 39-41 are normally closed. In operation for heating water the valve 25 is opened, which automatically causes the valve 7 to open, and the stem 8 to abut against and press against the stem 28 of the valve 26, thereby causing said valve 26 to open and permit the passage of fuel therethrough to the burner 12. The

jets 13 of the burner 12 are ignited by the pilot light and the water continues to circulate through the generator or heater 4, becoming rapidly heated in its tortuous passage therethrough. In generating steam, the valves 7 and 25 are closed. The generator or heater 4 is supplied with water, at uniform and constant pressure, from the supply tank 1. When the water in the generator has heated to a sufficient degree to develop steam the valve 39-41 automatically opens, and steam escapes through the ejector or aspirator 43, causing a strong draft or suction in the pipes 44 and 45. The auxiliary valve 31 is operated by the back-pressure of steam in the generator. When the pressure increases above a certain point a closure or partial closure of the valve 31 is effected, thus reducing the amount of fuel supplied to the burner 12, thereby causing the temperature in the heater or generator to fall, and the pressure to be reduced, causing the valve 31 to again open. Since the valve 31 is thus balanced, it is apparent that a constant and uniform pressure of steam will be maintained in the heater. The amount of fuel that passes through the valve 26 is regulated so that it corresponds to the quantity of water that passes through the valve 7. It will be observed therefore, that when the quantity of water drawn from the pipe 24 is increased, the supply of water passing through the valve 7 to supply the generator or heater must necessarily increase. When the system of piping in a building supplied by our present system includes a plurality of valves, instead of the single valve 25 a greater quantity of water may be drawn at one time, and the fuel supply for heating this increased supply will be relatively increased. Thus it will be seen that in our system only the requisite amount of fuel to heat a given quantity of water to a given temperature will be supplied, and no loss of heat will occur.

We are aware that several minor details in arrangement, construction, and design of the parts may be made, without departure from the spirit and scope of our invention, we do limit ourselves, therefore, to exact details, but

What we claim and desire to secure by Letters Patent of the United States is—

1. The combination with a generator, of a burner, a fuel supply pipe, a valve in said pipe, an outlet pipe from which hot water may be drawn from the generator, a second outlet passage leading from said generator, an aspirator located in said second named outlet passage manual means for opening the valve in said fuel supply pipe, and automatic means effective to permit a continuous passage of steam through said aspirator.

2. In a system of the character described, a generator, a water supply tank, a pipe

- from said water supply tank opening into the lower end of said generator, a passage from the upper end of said generator, a pipe from said water supply tank opening into 5 said passage, a valve chamber in said passage, a float valve in said valve chamber, and an aspirator passage leading from said valve chamber, substantially as specified.
3. In a system of the character described, 10 a generator, a water supply tank, a pipe from said water supply tank opening into the lower end of said generator, a valve chamber, a passage from the upper end of said generator to said valve chamber, a pipe 15 from said water supply tank opening into said passage, a pipe leading from said valve chamber, an aspirator in said pipe, and intake and outlet piping connected with said aspirator, substantially as specified.
- 20 4. In a system of the character described, the combination with a generator, a water service pipe therefor, a burner arranged to heat said generator, and a fuel service pipe for said burner, of an outlet passage leading 25 from said generator, a valve in said outlet passage, a second outlet passage from said generator, a valve in said passage, and a suction pipe entering said passage above said valve, substantially as specified.
- 30 5. In a system of the character mentioned the combination with a generator, a burner for heating said generator, a water service pipe for said generator, a fuel service pipe for said burner, a valve in said water serv- 35 ice pipe arranged to be automatically opened when water is drawn from said generator, a steam outlet passage from the generator, an aspirator in said passage, and a passage in communication with said last named passage, in which a suction is established by 40 the escape of steam through said aspirator, substantially as specified.
6. The combination with a generator, a burner arranged to heat said generator, and 45 a fuel supply pipe for said burner, of a valve in said fuel supply pipe, a second valve in said fuel supply pipe, a fluid motor controlled by the pressure in said generator for operating said second named valve, a 50 steam outlet passage from said generator, a valve in said passage controlled by pressure in said generator, and an aspirator in said passage, substantially as specified.
7. The combination with a generator, of 55 a burner arranged to heat said generator, a fuel service pipe for said burner, a valve
- in said service pipe, manual means for controlling said valve, automatic means for controlling said valve, a second valve in said fuel supply pipe, means for controlling said 60 second valve operated by the pressure in the generator, a steam outlet passage from the upper part of said generator, an aspirator in said steam outlet and an intake and outlet passage located beyond said aspirator, 65 substantially as specified.
8. In a system of the character described, the combination with a generator, of a water supply tank, a passage from said supply tank to the lower end of said generator, a 70 fuel burner arranged to heat said generator, a fuel service pipe for said burner, a valve in said fuel supply pipe, a passage from the upper end of said generator, an aspirator in said passage, a passage from the water 75 supply tank opening into the said last-named passage, and a valve for controlling the passage of steam through said aspirator for the purpose specified.
9. In a system of the character described, 80 the combination with a generator, of a water supply tank, a passage from said water supply tank opening into the end of said generator, a valve chamber, a float valve in said chamber, a passage from the upper end 85 of said generator to said valve chamber, a pipe from said water supply tank opening into said passage, a passage from said valve chamber and an aspirator in said last-named passage, substantially as specified. 90
10. In a system of the character described, the combination with a generator, of a tank arranged to supply water to said generator under pressure, a fuel burner arranged to heat said generator, a fuel supply pipe, a 95 valve in said fuel supply pipe, a water outlet from said generator, a steam outlet from said generator, a valve in said outlet, an aspirator in said outlet, and automatic means whereby the valve in said outlet may be operated for controlling the passage of steam through said aspirator, substantially as specified. 100
- In witness whereof, we have signed this application in the presence of two subscr- 105 ing witnesses.
